UNITED STATES PATENT OFFICE

105,705

DESIGN FOR A CLOCK OR SIMILAR ARTICLE

Caspar Landriet, Chicago, Ill.

Application May 6, 1937, Serial No. 69,187

Term of patent 14 years

To all whom it may concern:

Be it known that I, Caspar Landriet, a citizen of the United States, residing at 3116 South Halsted Street, Chicago, in the county of Cook and State of Illinois, have invented a new, original, and ornamental Design for a Clock or Similar Article, of which the following is a specification, reference being had to the accompanying drawing, forming part thereof.

Fig. 1 is a side elevational view of a clock showing my new design;

Fig. 2 is a front view; and

Fig. 3 is a top plan view.

I claim:

The ornamental design for a clock or similar article, substantially as shown.

CASPAR LANDRIET.
